UNITED STATES PATENT OFFICE.

GEORGE HARGREAVES AND SAMUEL A. BAUGH, OF DETROIT, MICHIGAN.

RAIL-BRACE.

SPECIFICATION forming part of Letters Patent No. 427,315, dated May 6, 1890.

Application filed January 14, 1890. Serial No. 336,958. (No model.)

To all whom it may concern:

Be it known that we, GEORGE HARGREAVES and SAMUEL A. BAUGH, citizens of the United States, residing at Detroit, in the county of Wayne and State of Michigan, have invented 5 certain new and useful Improvements in Rail-Braces, of which the following is a specification, reference being had therein to the accompanying drawings.

10 This invention relates to new and useful improvements in rail-braces; and the invention consists in the peculiar construction of a brace formed of the scrap in the manufacture of rails or in the utilization of old rails, heretofore the flange and stem of the rail having been useful only as scrap to be remelted, while the head of the rail has been utilized 15 by rerolling into steel bars of various shapes.

Our invention consists in utilizing the flange 20 and part of the stem of a rail for the manufacture of a rail-brace.

In the drawings which accompany this specification, Figure 1 is a perspective view of a section of a railway-rail. Fig. 2 is a perspective view of the flange and stem. Fig. 3 is a 25 side elevation of the blank, showing it partially manufactured into our improved rail-brace. Fig. 4 is a side elevation of the rail-brace complete as applied in use. Fig. 5 is a 30 side elevational view showing a modified form of manufacture. Fig. 6 is a side elevation showing the blank shown in Fig. 5 as made up into a completed brace. Fig. 7 is a plan view of the lower die, and Fig. 8 is a side elevation of 35 the upper and lower dies.

At the present time in the manufacture of steel rails there is a certain amount of waste at the end of each rail, which is slit off, which parts are wasted, except the head portion of 40 the rail, which is used by rerolling into any desired shape for steel bars. In the utilization of old rails for various purposes the head portion alone has been utilized to reroll into steel bars, while the flange and stem of the 45 rail have been used as scrap only.

A shows a railway-rail, of which *a* is the head, *b* is the flange, and *c* is the stem. To utilize this after the rail has been worn, or to use up the portion that was cut off in the 50 manufacture of the rail, the head portion *a* is cut from the stem portion in any suitable manner, leaving a T-shaped blank *B*, consist-

ing of the flange *b* and the stem *c* of the rail. This has heretofore been of little use except as scrap. In the manufacture of our rail-brace we utilize this blank *B*, cutting it into pieces of suitable length and bending one end or forging one end of suitable shape to form a bearing against the side of the rail. This we preferably do by forging the blank while 55 hot, first inserting it into a suitable die and bending the end into the head *d*, as shown in Fig. 3, substantially at right angles to the body portion *e*, and then in inserting the body portion *e* in a suitable receptacle in the bed 60 of the die, and forming it with the vertical portion *f* and the shoulder *g* so that it will 65 have a bearing against the side of the rail.

The dies that we use preferably consist of the bed *C*, which has at one end the recess *D*, 70 extending across the face of the bed, of suitable width and depth to receive the web *c* of the blank. When in this position, as shown in dotted lines in Fig. 7, a flat portion of the die *E* strikes the bottom of the flange and 75 trues up the cut edge of the web *c*. The blank is next laid on the bed with the web *c* in the recess *F*, with the end *d* extending beyond the side of the bed. The upper die is provided with a shoulder *G*, which strikes 80 this portion *d* of the blank and bends it, as shown in Fig. 3. The blank is now removed and placed in the vertical aperture *H*, bearing 85 with its lower end against an adjustable bearing-block *I*, while the upper die is formed at *J* with a particular shape to give the shape of the side of the rail to the bent portion or head *d* of the blank.

It is obvious that in bending the head *d* back against the body *e* the web will be enlarged between the head and body portion at *h*. This enlarged portion of the web forms a truss or support for the upper portion of the brace. It is evident that it will require considerable power, perhaps several blows of 90 a drop-hammer, to give the requisite form to this head. If it is desired to quicken or 95 simplify the manufacture of this part of the brace, we may cut away the V-shaped portion *i* of the web at the point where the bend is made in the blank to allow of the bending of the blank without injuring or buckling of the web portion of the metal, as shown in Fig. 5.

It will be seen that the portion *e* forms a

convenient body portion to be spiked upon the tie beside the rail, while the head portion *d* forms a wide bearing against the side of the rail. If desired, the body portion *e* may 5 be provided with suitable spike-holes *j*; but this we do not consider necessary.

What we claim as our invention is—

1. A rail-brace manufactured from the stem and flange of a rail and formed by forging a 10 side bearing for the rail at one end of the blank, substantially as described.
2. A rail-brace manufactured from the stem

and flange of a rail and formed by forging a side bearing for the rail in the flange, the stem forming a support or truss for said bearing, substantially as described. 15

In testimony whereof we affix our signatures, in presence of two witnesses, this 30th day of December, 1889.

GEORGE HARGREAVES.

SAMUEL A. BAUGH.
